UNITED STATES PATENT OFFICE.

MELVILLE CLARK, OF CHICAGO, ILLINOIS.

DESIGN FOR AN ORGAN-STOP KNOB.

SPECIFICATION forming part of Design No. 18,330, dated May 22, 1888.

Application filed April 27, 1888. Serial No. 272,063. Term of patent 7 years.

To all whom it may concern:

Be it known that I, MELVILLE CLARK, a citizen of the United States, residing at Chicago, in the county of Cook and State of Illinois, have invented and produced a new and original Design for Stop Knobs, which is shown in the accompanying sheet of drawings, wherein there appear in—

Figure 1, a side elevation; Fig. 2, a perspective; Fig. 3, a front elevation.

The body or neck of the knob in this design is circular in transverse outline about a curved axial line of less than ninety degrees (90°) curvature. The general direction of said axial line (that is to say, the chord of the arc) is oblique to the base, and said stem increases in diameter from an intermediate point both toward the base and toward the head, and its head is also circular and stands at an oblique angle at the base of the body or stem. Said head has a flat circular face with a beveled edge, and about said face there is a marginal portion of molded outline, which recedes from the face and constitutes a molded edge for the

head. The flat circular face is in a plane parallel with an imaginary plane which may be conceived as being the forward boundary of the portion called the "stem" or "body," which is the plane of the periphery of the molded edge, and said face is therefore oblique to the base of the body.

I claim—

The design for an organ-stop knob herein shown and described, in which the head has a flat circular face oblique to the base and surrounded by a molded margin receding from the circular face, and in which the stem or body is circular in transverse outline about an axis whose general direction is oblique to the base, said stem expanding from the middle portion toward the base and toward the head, substantially as set forth.

In testimony whereof I have hereunto set my hand this 24th day of April, 1888.

MELVILLE CLARK.
